UNITED STATES PATENT OFFICE.

JAMES PROWETT, OF PHILADELPHIA, PENNSYLVANIA.

BOTTLE SEAL OR CLOSURE.

1,042,267.

Specification of Letters Patent. Patented Oct. 22, 1912.

Application filed February 20, 1912. Serial No. 678,763.

To all whom it may concern:

Be it known that I, JAMES PROWETT, a citizen of the United States, residing at Philadelphia, in the county of Philadelphia and State of Pennsylvania, have invented new and useful Improvements in Bottle Seals or Closures, of which the following is a specification.

This invention relates to bottle seals or closures primarily designed for sealing or closing the mouths of milk jars and like receptacles, the object of the invention being to provide a seal or closure of the cap type which may be applied to securely seal the jar against the access of air, moisture and insects and yet may be readily removed and reapplied as occasion requires for the discharge of a portion of the contents of the bottle and the sealing of the bottle to prevent the remainder of the contents.

A further object of the invention is to provide a sealing cap which will frictionally grip the bead of the jar sufficiently to hold it against casual displacement, while permitting it to be readily applied and removed by an up or down sliding motion.

The invention consists of the features of construction, combination and arrangement of parts, hereinafter fully described and claimed, reference being had to the accompanying drawing, in which:—

Figure 1 is a vertical sectional view showing the application of the invention to a milk jar. Fig. 2 is a horizontal transverse section through the jar and cap. Fig. 3 is a detail vertical section on an enlarged scale through a portion of the mouth of the jar and the gripping portion of the cap flange. Fig. 4 is a bottom plan view of the cap. Fig. 5 is a view of the blank from which the cap is formed.

The cap comprises a circular top or crown portion 1 made of sheet metal and having a pendent annular or continuous flange 2. The flange 2 is continuously corrugated or has a wavy or fluted contour throughout, the inwardly projecting portions 3 of the corrugations forming gripping surfaces to frictionally engage the bead 4 of the mouth 50 of a milk jar or other similar receptacle.

The flange is of sufficient resiliency to adapt the bearing surfaces 3 to yield and react to slide over the bead 4 when the cap is applied by forcing it downward under pressure, so that said bearing surfaces will conform to the contour of the bead and grip

the same with sufficient firmness to hold the cap under all conditions from casual displacement. In order to secure an effective bearing action, the bearing surfaces are preferably flattened from a truly arcuate shape by which they are strengthened and reinforced to increase their resilient pressure. The lower edge 6 of the flange is also preferably of a corrugated, wavy or fluted outline, being formed with lips or depending portions 7 in line with the bearing surfaces, thus increasing the depth of the latter. These lips conform to the shape of the bearing surfaces and are bent inwardly slightly so as to engage beneath the point of greatest diameter of the bead, to further increase the holding action of the cap.

In practice, the cap may be made of spring sheet metal or other suitable material, and is designed particularly for use on milk bottles and other receptacles which are occasionally opened for the discharge of a portion of their contents and sealed for the preservation of the remainder of the contents. Such receptacles may be opened and closed a number of times before the contents is fully exhausted, and a seal must, therefore, be provided which, while inexpensive of construction, may be applied and removed with facility without injury thereto or impairing its sealing qualities. My invention provides a cap or seal which possesses these desirable advantages, and one which may be preserved and transferred from day to day from one bottle to another to take the place of the usual inefficient and insanitary paper seal commonly employed. In this respect my invention differs radically from corrugated caps of that character which are positively fastened or locked in sealing position upon the container, which require the use of an extracting tool for their removal, and which are designed to be used once only and, in fact, are incapable of being but once employed, as they are destroyed and rendered unfit for further use to effect a tight seal during the operation of extraction. My cap or seal is further advantageous in that the described form of the corrugations prevents the accumulation of dirt or clotted portions of the contents of the bottle therein, while permitting the cap to be scalded and cleaned until absolutely sterile.

A moisture-proof paper seal or liner 8 may be employed in conjunction with the

cap to seal the jar or receptacle hermetically.

Having thus described the invention, what I claim as new is:—

- 5 A bottle cap stamped from sheet metal and comprising a crown portion formed with a depending flange, said flange being provided along its lower edge at regular intervals with spaced segmental lips and having its body portion formed with semi-elliptical indentations between its top and bottom edges and in axial alignment with said lips, whereby the flange is fluted or corrugated throughout its circumference, the indentations or inwardly extending portions
- 10
- 15

of said corrugations being slightly flattened to provide gripping surfaces and the depending portions of the corrugations arranged to merge into the lips, the latter being longitudinally and transversely curved 20 and projected inwardly to provide horizontal gripping projections in line with the vertical gripping surfaces.

In testimony whereof I affix my signature in presence of two witnesses.

JAMES PROWETT.
